DESIGN FOR A BUTTON

William E. Stanbury, Kansas City, Mo., assignor to Verbury, Inc., Kansas City, Mo., a corporation of Missouri

Application March 24, 1937, Serial No. 68,362

Term of patent 14 years

To all whom it may concern:

Be it known that I, William E. Stanbury, a citizen of the United States, residing at Kansas City, in the county of Jackson and State of Missouri, have invented a new, original, and ornamental Design for a Button, of which the following is a specification, reference being had to the accompanying drawing forming part thereof, in which

I claim:

The ornamental design for a button, substantially as shown.

WILLIAM E. STANBURY.
